CAN SHIFTING DEVICE FOR CAN
WASHING MACHINESJohn M. McClatchie, New York, N. Y., assignor
to The Borden Company, New York, N. Y., a
corporation of New JerseyOriginal application October 7, 1933, Serial No.
692,552. Divided and this application Septem-
ber 12, 1934, Serial No. 743,634

3 Claims. (Cl. 198—25)

The present invention relates to an improvement in can shifting devices for can washing machines. This application is a division of my co-pending application filed October 7, 1933, Serial No. 692,552.

In my Patent No. 1,914,145, dated June 13, 1933, there is disclosed a can washing machine provided with a transporting carriage having an upward, forward, downward and backward movement for successively depositing the cans in inverted position over a series of nozzles and then uprighting the cans on a platform. An oscillating arm travels in a slot in the platform and when a can has been deposited on the platform, the arm pushes the can across the platform into position to receive a cover. With the use of an oscillating pusher arm, it is difficult to adjust the timing of the oscillations of the arm with the placing of the can in upright position on the platform.

One object of the present invention is the provision of improved means in the form of a rotating arm for pushing the cans across the platform, so as to avoid any possible interference between the arm moving to can-pushing position and the can being deposited on the platform. Another object of the invention is the provision of a guard plate which is moved across the slot in the platform (that is to say, across the path of travel of the can on the platform), just before the can lands on the platform, and which is moved out of the path of the can across the platform just before the pusher arm moves the can.

In the accompanying drawings illustrating so much of the can washing machine shown in said application and in said patent as is necessary to disclose the construction and mode of operation of the devices of the present invention, Fig. 1 is a plan view of the discharge end of the can washing machine to which the improved can shifting devices are applied; Fig. 2 is a rear end elevation of the parts shown in Fig. 1; Fig. 3 is a side elevation, partly in section, and looking from the right, of the parts shown in Fig. 1; Fig. 4 is a section in elevation of the pusher arm driving means; and Fig. 5 is a top plan, partly in section of the parts shown in Fig. 4.

The can transporting means, which is the same as in said patent, comprises a frame indicated at 10 and a can supporting rail 11. The upward, forward, downward and backward movement is imparted to the carriage by two internal rectangular gears 12 (only one shown), driven by a pinion 14 fixed on one end of a shaft 15, on the

other end of which is mounted a bevel gear 16 meshing with the gear 17 mounted on shaft 18 driven by the chain 19 and sprocket wheel 20.

The carriage 10 advances the cans 23 in inverted position along a can support 22 consisting of two horizontal bars and successively places them over nozzles 24 by which they are subjected to a cleansing and sterilizing treatment in the usual way. When a can is placed over the last or air nozzle 26, one edge of the mouth 10 of the can rests on a block 27 and the opposite edge of the mouth of the can rests on the support 22, so that the can tips toward an abutment 28, as shown in dotted lines 29 in Fig. 3. On the final backward movement of the carriage (with respect to the can over the nozzle 26) the forward edge 31 of the carriage is in alignment with about the center of the can, so that on the next upward movement of the carriage the can is thrown forward against the abutment 28, as shown at 32, and as the carriage continues to rise is somersaulted or toppled over the abutment into upright position on a platform 33, as shown by the can 35. If the can does not fully go over the abutment on the upward stroke of the carriage, it is pushed thereover at the beginning of the next forward stroke of the carriage.

The platform 33 extends transversely across the discharge end of the machine and is supported from the frame of the machine. To assure the proper uprighting of the can on the platform, a forward guard plate 37 and side guard plate 38 are provided, rising from the platform. Cooperating with these fixed guard plates is a movable guard plate 40 secured at one of its edges to a vertical shaft 41 mounted to oscillate in bearings 42. At its lower end the shaft 41 connects through a toggle 43 with a rod 44 pivotally connected with an arm 45 secured to a shaft 46 journaled in bearings 47.

The shaft 46 is oscillated by the upward and downward movements of the can transporting carriage. Fixed on the shaft 46 by the hub 49 is an arm 50 arranged to slide in a sleeve 51 the head 52 of which is arranged to slide longitudinally on a rod 54 secured at both ends in a downward extension 55 of the internal gear 12. To prevent the sleeve from cramping on the rod 54 guards 53 are provided. This arrangement is such that while the carriage is moving forward and a can is falling into upright position on the platform, in the position shown by dotted lines 57 in Fig. 1. As the carriage begins to descend, the oscillation of the shaft 46 by the sleeve 51 55

causes the plate 40 to be swung into the position shown in full lines, in which position it remains while the carriage travels rearwardly or toward the right in Fig. 1. On the next upward stroke 5 of the carriage, the plate 40 is again swung across the platform.

A further means of assuring the proper up-righting of the cans on the discharge platform is a pusher arm 59 rising from a transverse shaft 10 60 and normally located between the arms of the U-shaped abutment 28, as shown in Fig. 1. On the outside end of the shaft is fixed an arm 62 leaning toward the carriage, on which at this point is fixed a stud 63, so that on the forward 15 stroke of the carriage the engagement of the stud 63 with the arm 62 causes the shaft 60 to be oscillated and the pusher arm 59 to be brought against the can descending onto the platform and so assist in settling it in upright position. On 20 the return stroke of the carriage, the arms 59 and 62 fall by gravity into normal position.

On the down stroke of the carriage the can which has just been deposited on the platform is pushed across the platform into position to receive a cover 65 from a cover runway 66. The means for pushing the can across the platform comprises a rotating arm 68 having an enlarged can-engaging end 69. The arm 68 is mounted on a shaft 70 on which is fixed a sprocket wheel 71 30 connected by the chain 72 with the sprocket wheel 73 mounted on the shaft 74. On the inner end of the shaft 74 is mounted a pinion 76 which meshes with a pinion 77 mounted on the shaft 78 extending at right angles to the shaft 74. On 35 the inner end of the shaft 78 is fixed a bifurcated arm 80 loosely embracing a pin 81 fixed in the extension 55 of the gear 12. By means of this arrangement the arm 68 is given a rotary movement.

40 Since the can transporting carriage and the gear 12 have a rectangular path of travel—upward, forward, downward and backward—the pin 81 mounted on the lower part of the gear 12 will occupy different positions in the slot in the arm 45 80, that is, positions at varying distances from the shaft 78, according to the position of the gear 12 in its path of travel. The pin 81 is constantly moving, and so the shaft 78 is constantly turning and with it the arm 68. But the speed of 50 rotation of the shaft 78 and of the arm 68 varies according to the position of the pin 81 in the slotted arm 80. This variation in the speed of travel of the arm 68 is availed of to push the can across the platform 33 in such manner as to avoid toppling the can over.

When the carriage has completed its forward movement, after having somersaulted the can over the abutment 28, the pin 81 is near the end 60 of the slot in the arm 80 and so the arm 68 is moving relatively slowly, and while it is in this movement it is brought into contact with the can which has just been uprighted on the platform. This occurs as the pinion 14 rounds the upper left hand corner of the gear 12, viewing Fig. 3, when 65 the pin 81 is farthest from the shaft 78. In this connection it will be understood that the arm 68 can be adjusted on the shaft 70, with respect to the positions of the pin 81 and arm 80. The slow movement of the arm 68 continues as the carriage 70 begins to descend with the result that the can is gently started across the platform. As the carriage descends the pin 81 approaches nearer to the shaft 78, and so the speed of the arm 68 accelerates, until the pin is opposite the middle 75 of the gear 12. The can is now about half way

across the platform. After the pinion 14 passes the middle portion of the left hand upright portion of the gear 12, the movement of the shaft 78 and of the arm 68 decreases in speed until the pinion 14 reaches the lower left hand corner of the gear 12 at which point the arm 68 has pushed the can clear across the platform and is descending through the slot 83. It will thus be seen that in its movement across the platform 33 the can is first gently engaged by the arm 68 and moved slowly, but with accelerating speed until it is about half way across the platform, and then that the speed of travel of the arm 68 and can gradually diminishes until the can reaches its final position under the cap runway 66. 15

The platform 33 is provided with a slot 83 to accommodate the arm 68 as it pushes the can across the platform. At one end of the slot 83 is an enlargement 84, and at the other end an enlargement 85 to accommodate the head 69 of the arm 68. The enlargement 84 is to one side of the spot where the uprighted can lands on the platform (which is opposite the ends of the can support 22), so that when during the rotation of the arm 68 the head rises through the enlargement 25 84 it will be in position to engage one side of the can which has just been uprighted, and is indicated at 87 in Fig. 1. As the arm 68 completes the upper arc of its rotation it pushes the can into cover-receiving position indicated by the 30 broken lines 88. This position of the can is determined by the rails 91 and 92. The cover 65 is caused to descend into the can in the manner described in said patent.

When its cover has been received by the can, 35 the latter is pushed onto the rolls 94, and so out of the machine, by means of an arm 95 attached to a forward extension 96 of the can carriage. The platform 33 is slotted at 97 to accommodate the arm 95. 40

The parts illustrated in the drawings but not described herein are essential elements of the complete can washing machine disclosed in said patent, but do not directly cooperate with the novel can shifting devices herein claimed. 45

I claim as my invention:—

1. In a machine of the character described including a can transporting carriage having an upward, forward, downward and backward movement, a platform, and means for up-righting a can onto the platform, a rotatable arm for moving the can across the platform and means for rotating the arm comprising a shaft on which the arm is mounted, and connections between the shaft and the carriage for giving the shaft a varying speed of rotation according to the direction of travel of the carriage, said arm being arranged with respect to its driving means to be brought into contact with the can at substantially its slowest rate of movement. 60

2. In a machine of the character described including a can transporting carriage having an upward, forward, downward and backward movement, a platform, and means for up-righting a can onto the platform, a rotatable arm for moving the can across the platform, and means for rotating the arm with varying speed comprising a shaft on which the arm is mounted, a second shaft, driving connections between the first and the second shafts, a slotted arm mounted on the second shaft, and a pin connected with the carriage and received in the slot of the slotted arm whereby the can-pushing arm is given a varying speed of rotation according to the direction of travel of the carriage, said can-pushing arm be- 75

ing arranged to contact with the can as the pin begins its downward travel.

3. In a machine of the character described including a can transporting carriage having an upward, forward, downward and backward movement, a slotted platform, and means for uprighting a can onto the platform over the slot, a rotatable arm adapted to travel in the slot for moving the can across the platform, and means for rotating the arm comprising a shaft on which the

arm is mounted, a second shaft, driving connections between the first and second shafts, a slotted arm mounted on the second shaft, and a pin connected with the lower end of the carriage and received in the slot of the slotted arm whereby as the carriage travels in its rectangular path the pin travels in the slot and thereby rotates the second shaft so as to give the can-pushing arm a varying speed of rotation.

JOHN M. McCLATCHIE. 10
